UNITED STATES PATENT OFFICE.

JOHN POKOJNÍ, OF NEW YORK, N. Y.

DESIGN FOR A MINIATURE SHRINE.

54,332.

Specification for Design.

Patented Dec. 23, 1919.

Application filed August 28, 1919. Serial No. 320,537. Term of patent 7 years.

To all whom it may concern:

Be it known that I, JOHN POKOJNÍ, a citizen of Czecho-Slovakia, residing at New York, in the county of New York and State of New York, have invented a new, original, and ornamental Design for Miniature Shrines, of which the following is a specification, reference being had to the accompanying drawing, forming part thereof.

The figure is a view in perspective of a miniature shrine, showing my new design.

I claim:—

The ornamental design for a miniature shrine, as shown.

JOHN POKOJNÍ.
